UNITED STATES PATENT OFFICE.

WILLIS S. SHAFT, OF FARIBAULT, MINNESOTA, ASSIGNOR TO SHAFT-PIERCE SHOE COMPANY, OF FARIBAULT, MINNESOTA.

MEANS FOR ATTACHING SHOE BUCKLES.

Application filed January 25, 1927. Serial No. 163,494.

This invention relates to fasteners and more particularly to novel means for retaining buckles in position.

The primary object of the present invention is the provision of novel means for securing shoe buckles in place on the upper, the means employed being susceptible for other uses, such as for securing belt buckles, harness buckles and the like in place.

Another object of the invention is the provision of means for securing a buckle on a shoe by the use of a single retaining strap, only one thickness of the strap being sewed to the upper, thereby facilitating the attaching of the buckle to the upper and insuring the proper thinness to the upper without the distortion thereof and the consequent uncomfortable wear of the shoe.

A further object of the invention is the provision of a novel retaining strap for shoe buckles having a slot formed therein transversely thereof and adjacent to one end, the strap being adapted to be folded around the middle bar of the buckle and threaded through said slot and then attached to the upper, the threading of the strap through the slot forming an effective loop for holding the middle bar of the buckle and thereby insuring the holding of the buckle to the strap without the use of thread, steel fasteners or the like.

A further object of the invention is the provision of novel means for forming a pocket in a shoe upper for the reception of the free end of the retaining strap of the buckle whereby the retaining strap will be normally hid from view and thereby form a neat and attractive shoe.

A still further object of the invention is the provision of novel means for retaining the shoe buckles on a shoe upper of the above character, which will be durable and efficient in use, one that will be simple and easy to manufacture and one which can be connected with the shoe at a small cost.

With these and other objects in view, the invention consists in the novel construction, arrangement and formation of parts, as will be hereinafter more specifically described, claimed, and illustrated in the accompanying drawings, in which drawings:

Figure 1 is a side elevation of a child's sandal showing the invention applied thereto, Figure 2 is a fragmentary longitudinal

section showing the means of associating the retaining strap with the buckle and the pocket formed in the upper for receiving the strap,

Figure 3 is a section through the shoe upper taken on the line 3—3 of Figure 1 looking in the direction of the arrows showing the buckle in place,

Figure 4 is a section taken on the line 4—4 of Figure 1 looking in the direction of the arrows showing the strap secured in place,

Figure 5 is an elevation of a shoe buckle and retaining strap showing the inside thereof, and

Figure 6 is a perspective view of the novel retaining strap of the buckle prior to association thereof of the buckle.

Referring to the drawings in detail, wherein similar reference characters designate corresponding parts throughout the several views the letter A indicates the shoe, which in the present instance has been shown to be of the sandal type, B a buckle and C the novel retaining strap.

As stated the shoe A has been shown to be of the sandal type and is of the usual or any preferred construction. The upper 10 is provided with any preferred type of lining 11, the longitudinal instep or flap 12 and the ankle and instep retaining straps 13 and 14. The ankle and instep straps 13 and 14 are secured to the upper at one side thereof in the usual way and are threaded through loops 15 carried by the tongue or longitudinal instep strap 12.

The buckles B are connected to the opposite sides of the upper from the straps or the point of fastening of the straps 13 and 14 and as shown the upper 10 is provided with slits 16 which define pockets 17 between the upper 10 and its lining 11 for the retaining straps C. The buckles B are of the usual character and include the side bars 20, the end bars 21 and 22 and the middle bar 23 on which is rockably mounted the belt buckle tongue or prong 24.

The fastening strap includes an elongated body portion 25 having the opposite sides thereof at one end cut to provide a point 26 to facilitate the insertion of the strap in the pocket 17. The opposite end of the strap is provided with a flared end 27 which is provided with a transverse slot 28 for a purpose which will be hereinafter more fully

described. The body 25 of the strap inward of the slot 28 is provided with a longitudinal slot or slit 29 the purpose of which will also hereinafter more fully appear as the description proceeds.

In accordance with this invention the strap C is threaded through the buckle C over the middle bar 23 thereof and the prong 24 is placed through the slit 29, the flared head 10 27 of the strap being placed near the bar 21 of the buckle. The strap is now folded and the leading point 26 of the strap is threaded through the slot 28, which forms a loop 30 straddling the bar 23. The buckle is now 15 ready to be placed in position and the leading point of the strap is placed through the slit 16 and the strap is then forced into the pocket. The strap is now held in place on the upper in any preferred way, such as by 20 use of stitching 31 as clearly shown in the drawings.

By this arrangement only a single thickness of strap is secured to the upper and the strap only has to be sewed at one point and 25 the entire arrangement prevents the accidental displacement of the buckle from the upper.

If desired the strap can gradually decrease in thickness toward the leading point 26 so 30 as to facilitate threading of the strap into the slot 28 and the forcing of the strap into the pocket without materially increasing the thickness of the upper. This also insures the strength of the strap at the point of 35 connection therewith with the buckle.

While I have shown the pocket formed between the upper and its lining, it is to be understood that the strap can be secured to the outer or inner face of the upper without departing from the spirit or the scope of 40 this invention.

Changes in details may be made without

departing from the spirit or scope of the claims.

I claim:

1. The combination with a shoe including an upper and a buckle therefor having middle and end bars, of means for retaining the buckle on the upper including a strap having a transverse slot therein at one end 50 folded about one of said bars with the end remote from the slot threaded through the slot, said end constituting a single attaching tab and means connecting the tab with the upper.

2. The combination with a shoe including an upper and a buckle including middle and end bars, of a strap for securing the buckle to the upper comprising an attaching tab and a flared head at one end of the 60 tab having a transverse slot, the head being folded about the middle bar of the buckle with the tab threaded through the slot, and means for securing the free end of the tab on the upper.

3. The combination with a shoe including an upper having a lining and a buckle including a middle bar, end bars, side bars and a prong, of a strap for connecting the buckle to the upper, the upper having a slit, 70 the strap comprising an attaching tab tapered at one end and a flared head at the opposite end provided with a transverse slot, the strap adjacent to the head being provided with a longitudinal slit, the head being folded about the middle bar of the buckle through the slit, the tab being threaded through the slot to form a loop for snugly embracing the cross bar, the tab being inserted in the 80 slit and between the upper and lining and stitching connecting the tab to the upper.

In testimony whereof I affix my signature.

WILLIS S. SHAFT.
